[57] CLAIM

The ornamental design for a refillable, liquid dentifrice dispenser and toothbrush holder, as shown and described.

DESCRIPTION

FIG. 1 is a front perspective view of a refillable, liquid dentifrice dispenser and toothbrush holder with its top cover in place, showing my new design;

FIG. 2 is a right hand side elevation view thereof, the opposite side elevational view being a mirror image of that shown;

FIG. 3 is a back elevation view thereof;

FIG. 4 is a front elevation view thereof;

FIG. 5 is a top plan view thereof; and,

FIG. 6 is a bottom plan view thereof.
